UNITED STATES PATENT OFFICE.

WILLIAM E. GREENE, OF RIVERSIDE, CALIFORNIA.

BINDER.

Application filed July 29, 1927. Serial No. 209,372.

This invention relates to improvements in binders.

The principal object of this invention is to produce a binder for use in holding together 5 various objects such as bee hives, boxes shook and the like.

Another object is to produce a device which will securely bind a plurality of objects and maintain the same against 10 accidental displacement.

A further object is to produce a device which may be lengthened so as to accommodate various sizes of bundles.

A still further object is to produce a 15 device which is economical to manufacture.

Other objects and advantages will be apparent during the course of the following description.

In the accompanying drawings forming 20 a part of this specification and in which like numerals are employed to designate like parts throughout the same,

Figure 1 is a side elevation of my device as the same would appear in use,

25 Figure 2 is an end elevation of Figure 1,

Figure 3 is a side elevation of a lengthening clip and lengthening strip, and

Figure 4 is a top plan view of Figure 3.

There are many instances where it is desired 30 to fasten together several boxes and bundles so that the same may be held against accidental displacement while positioned or during transportation.

In the raising of bees, hives are often 35 placed where they are liable to be disturbed thereby liberating the bees, unless some securing means is employed.

By employing my binder, the accidental 40 displacement of the hive is eliminated yet when desired, the binder may be quickly removed, and a superframe placed upon the top of the hive, a linking strap inserted in my binder and the same retightened so as to hold the superframe and the hive in fixed 45 position.

In the accompanying drawing wherein 50 for the purpose of illustration is shown a preferred embodiment of my invention, the numeral 5 designates a bee hive, the numeral 6 a strap of relatively heavy material. The reason for making this strap relatively heavy is that as the hive is usually set upon the ground, the strap would quickly rust were it not made of heavy material.

55 The ends of this strap are provided with slots through which screws 7 are placed one

at each end. An offset spring 8 is secured to the strap 6 and contacts the underside of the hive. The purpose of this spring will be later seen.

60

Upon one end of the strap I secure an offset strip 9 which is riveted to the strap 6. This virtually forms a bifurcated end for the reception of the end 11 of a binding strap 12. This binding strap 12 has perforations formed therein as shown at 13, Figure 4. A pin 14 is passed through the end of the strap 6, the end of the strap 12 and the offset strip 9 after which a cotter pin 16 is placed therethrough. To the opposite 65 end of the strap 6 is secured an offset toothed member 17 which is adapted to be engaged by a pin 18 of a compression lever 19. A ring 21 has pivoted connection to the compression lever 19 and to a bifurcated clamp 70 75 22. This bifurcated clamp is adapted to have the end of the strap 12 pass therebetween and a pin 23 inserted in a manner similar to the pin 14. The result of this construction is that a strap 6 is secured to 80 each of the hives by fastening its ends with screws 7 after which the strap 12 is secured to the end containing the pin 14 which strap is then carried over the top of the 85 hive and is engaged with the clamp 22.

By now employing the compression lever 19 and causing the pin 18 to move into one of the teeth of the offset member 17, the result will be that when the handle 19 is pushed downwardly into parallel alignment 90 with the side of the hive tension will be placed on the strap 12 which tension will be maintained throughout the time that the strap is employed by the spring 8, and when it is desired to lengthen the strap 12 a supplemental strap may be employed, which supplemental strap is designated at 24, Figure 3.

The end of the strap 12 and the end of the strap 24 may be joined by a U-shaped clip 100 26 through which a pin 27 is inserted and held against misplacement by a cotter pin 28.

It will thus be seen that I have produced a device which is capable of binding articles 105 irrespective of the girth of the article to be strapped.

It is to be understood that the form of my invention herewith shown and described is to be taken as a preferred example of the 110 same and that various changes relative to the material, size, shape and arrangement

of parts may be resorted to without departing from the spirit of the invention or the scope of the subjoined claims.

Having thus described my invention, I claim:-

1. In a binding device, a strap having a bifurcated end, said strap being movably secured to the article to be strapped, a second strap having one of its ends engaged by the bifurcated end of the first mentioned strap, a clamp secured to the opposite end of said second mentioned strap, an offset toothed member secured to one end of said first mentioned strap, a compression lever 10 pivotally secured to said clamp and adapted to engage said toothed member for the purpose specified.

2. A binder, a strap, means for slidably engaging the ends of said strap with article to be bound, an offset spring interposed between said strap and article to be bound, an offset toothed member secured to one end of said strap, the opposite end of said strap having a bifurcated end, a second strap removably secured in said bifurcated end of said first mentioned strap, the opposite end of said second mentioned strap having a clamp secured thereto, a compression lever pivotally connected to said clamp and adapted to engage the teeth of said offset toothed member.

In testimony whereof I affix my signature.

WILLIAM E. GREENE.
